CLAIM

I claim the ornamental design for an ice shaver lid, as shown and described.

DESCRIPTION

FIG. 1 is a perspective view of an ice shaver lid showing my new design;

FIG. 2 is a side view thereof;

FIG. 3 is an opposite side view thereof;

FIG. 4 is a front view thereof;

FIG. 5 is a rear view thereof;

FIG. 6 is a top view thereof; and,

FIG. 7 is a bottom view thereof.

(Continued)

The broken lines shown in the drawings are for illustrative purposes only and form no part of the claimed design.
